UNITED STATES PATENT OFFICE.

HENRY H. AKERS, OF CHERRYVALE, KANSAS, ASSIGNOR TO H. H. AKERS MANUFACTURING COMPANY, OF CHERRYVALE, KANSAS.

MAIL-BAG CATCHER AND DELIVERER.

No. 888,414.

Specification of Letters Patent.

Patented May 19, 1908.

Application filed September 28, 1907. Serial No. 395,006.

To all whom it may concern:

Be it known that I, HENRY H. AKERS, a citizen of the United States, residing at Cherryvale, in the county of Montgomery and State of Kansas, have invented a new and useful Mail-Bag Catcher and Deliverer, of which the following is a specification.

This invention relates to mail bag catchers and has for its object to provide a comparatively simple and inexpensive device of this character especially designed for attachment to a rail-road car and by means of which mail bags or sacks may be delivered to and discharged from the car while the latter is in motion.

A further object of the invention is to provide a fork having a pivoted catch associated therewith and adapted to engage and retain the mail sacks in position on the fork.

20 A further object is to provide means for limiting the pivotal movement of the catch, and means for suspending a mail bag from the closed end of the fork and in position to be delivered at any particular station along 25 the route.

30 A further object is to provide the actuating spring with a sectional casing which assists in limiting the pivotal movement of the catch and also serves to receive the impact of 35 the mail bag and thus prevent injury to said spring.

35 A further object is to increase the length of the fork carrying arm or flange so that the mail cranes may be set back from the track and thus permit the engineer or fireman to make the usual observation without danger of striking said cranes.

40 A still further object of the invention is to generally improve this class of devices so as to increase their utility, durability and efficiency.

45 Further objects and advantages will appear in the following description, it being understood that various changes in form, proportions and minor details of construction may be resorted to within the scope of the appended claims.

50 In the accompanying drawings forming a part of this specification: Figure 1 is a top plan view partly in section of a mail bag catcher and delivery device constructed in accordance with my invention. Fig. 2 is an end elevation partly in section of the same. Fig. 3 is a side elevation of the fork. Fig. 4

is a transverse sectional view taken on the 55 line 4—4 of Fig. 1.

Similar numerals of reference indicate corresponding parts in all of the figures of the drawings.

The improved device forming the subject 60 matter of the present invention is principally designed for attachment to mail cars and similar vehicles and by way of illustration is shown in position on a mail car of the ordinary construction in which 5 designates one 65 side of the car and 6 the door opening.

Secured to the door casing 6 in any suitable manner, as by bolts or similar fastening devices 7, are brackets 8 in which is journaled a transverse shaft 9, said brackets being provided 70 with segmental bearing surfaces 10 which engage the correspondingly curved edges of the frame of the door opening.

Secured to and mounted for rotation with the shaft 9 is a relatively long arm 11 having 75 its upper face provided with a flat bearing surface 12 and its terminal portion cut away to form oppositely disposed stop shoulders 13 and 14.

Secured to the free end of the arm 11 is a 80 fork 15 the free end of which is inclined laterally so as to guide the mail bag to a recess or pocket formed by the closed end of said fork, as shown.

Pivottally mounted for swinging movement 85 on the arm 11, at the cut away portion 16, is a spring actuated catch having angularly disposed arms 16 and 17, there being a relatively short arm or extension 18 formed at the junction of the arms 16 and 17 for pivotal connection with the arm 12, as indicated at 19.

Fastened in an eye 20 on the free end of the arm 16 is one end of a coiled spring 21 the opposite end of which is secured in any suitable manner to the arm 12. It will thus be seen 95 that when a lateral pressure is exerted on the arm 16 of the catch the tension of the spring 21 will force the arm 17 transversely across the closed end of the hook and thus securely lock the mail bag in position on the fork. 100

Surrounding the spring 21 is a metal casing or housing 23 preferably formed in three sections which, when the spring is expanded are separated but are forced in contact with each other when the spring is contracted thereby 105 to assist in limiting the pivotal movement of the catch.

Attention is here called to the fact that the

sectional casing 23 not only serves to assist in limiting the pivotal movement of the catch but also serves to house the spring and receive the impact of the mail bag when the latter is delivered to the fork. It will also be observed that the pivotal movement of the catch in one direction is limited by the shoulder 14 while the pivotal movement of the catch in the opposite direction is limited by the shoulder 13.

By making the fork supporting arm 11 relatively long the mail cranes along the route may be set back from the track so as to permit the engineer or fireman to make the usual observations without danger of striking said cranes.

A rubber or other yieldable section 7' is preferably interposed between the base of the arm 11 and the adjacent bracket 8 to form a bumper and thus receive and absorb the impact of said arm when a mail bag is being delivered to the car.

When the catch is in the position shown in Fig. 1 of the drawings the spring is disposed to one side of the pivot point 19 so as to normally and yieldably force the arm 17 of the catch in engagement with the adjacent stop shoulder 14. With the parts in this position and a train traveling in the direction of the large arrow, indicated in Fig. 1 of the drawings, the mail bag will be forced in contact with the free end of the arm 16 thus partially tilting said arm and causing the spring 21 to move the relatively long arm 17 to a position transversely across the closed end of the fork and thus lock the bag on the fork so that the same may be conveniently removed by the operator.

A hook 24 is preferably secured to the lower face of the fork 15 at the closed end thereof for suspending a mail bag or sack in position to be delivered at any particular station along the route. A handle 25 is also preferably formed on the arm 11 so that the fork and its associated parts may be swung downwardly in contact with the side of the car when the device is not in use.

From the foregoing description it is thought that the construction and operation of the device will be readily understood by those skilled in the art and further description thereof is deemed unnecessary.

Having thus described the invention what is claimed is:

5. 1. The combination with a car having an opening formed therein, of a fork extending transversely across the opening, a catch co-acting with the closed end of the fork, a spring connecting with the catch and fork, respectively, and a sectional casing surrounding the spring and serving to house the latter.

2. The combination with a car having an opening formed therein, of a shaft journaled on the car and extended transversely across the opening, an arm secured to and movable

with the shaft, a fork carried by the free end of the arm, a spring actuated catch pivotally mounted on the arm and movable to operative position at the closed end of the fork, a spring connecting the catch and arm, respectively, and a sectional casing surrounding the spring and forming a housing for the latter.

3. The combination with a car having an opening formed therein, of a fork extending transversely across the opening, a pivoted catch co-acting with the closed end of the fork, means for limiting the pivotal movement of the catch, a spring connecting the fork and catch, respectively, and a sectional casing surrounding the spring, said casing serving to house the spring and assist in limiting the pivotal movement of the catch in one direction.

4. The combination with a car having an opening formed therein, brackets secured to the side of the car, a shaft journaled in said brackets and provided with a laterally extending arm the free end of which is reduced to form oppositely disposed stop shoulders, a fork carried by the arm, a spring actuating catch pivotally mounted on the reduced end of the arm and movable to operative position across the closed end of the fork, and a spring connecting the catch and arm, respectively, the pivotal movement of the catch being limited by engagement with the adjacent stop shoulders.

5. The combination with a car having an opening formed therein, brackets secured to the side of the car at said opening, a shaft journaled in the brackets and provided with a laterally extending arm the free end of which is reduced to form oppositely disposed stop shoulders, a fork secured to the arm, a catch pivotally mounted on the reduced end of the arm and co-acting with the closed end of the fork, a spring having one end thereof secured to the catch and its opposite end fastened to the arm, and a sectional casing surrounding the spring and forming a housing for the same.

6. The combination with a car having an opening formed therein, brackets secured to the side of the car, a transverse shaft journaled in said brackets, an arm extending laterally from the shaft and having its free end reduced to form oppositely disposed shoulders, a fork extending laterally from the arm, a catch co-acting with the fork and provided with angularly disposed arms one of which is movable to operative position at the closed end of the fork, an extension formed at the juncture of said arm and having a pivotal connection with the reduced end of the laterally extending arm, and a spring forming a yieldable connection between the laterally extending arm and catch.

7. The combination with a car having an opening formed therein, brackets secured to

the side of the car at said opening, a shaft journaled in said brackets, an arm extending laterally from the shaft and having its free end reduced to form oppositely disposed 5 stop shoulders, a fork carried by the arm, a spring actuating catch pivotally mounted on the reduced end of the arm and co-acting with the closed end of the fork, a spring connecting the arm and catch, respectively, a 10 sectional casing surrounding the spring and forming a housing for the latter, and a bag engaging hook depending from the closed end of the fork.

8. The combination with a car having an 15 opening formed therein, brackets secured to the side of the car at said opening, a shaft journaled in said brackets, a relatively long arm extending laterally from the shaft and having its free end reduced to form oppositely

disposed stop shoulders, a fork carried by the 20 arm, a spring actuated catch pivotally mounted on the reduced end of the arm and co-acting with the closed end of the fork, a spring forming a yieldable connection between the catch and arm, respectively, and 25 a yieldable packing interposed between the arm and the adjacent bracket, the pivotal movement of the catch being limited by engagement with the adjacent shoulders on 30 said arm.

In testimony that I claim the foregoing as my own, I have hereunto affixed my signature in the presence of two witnesses.

HENRY H. AKERS.
